UNITED STATES PATENT OFFICE

GEORGE SAKIER, OF NEW YORK, N. Y., ASSIGNOR TO FOSTORIA GLASS COMPANY, OF MOUNDSVILLE, WEST VIRGINIA, A CORPORATION OF WEST VIRGINIA

DESIGN FOR A TUMBLER OR SIMILAR ARTICLE

Application filed October 28, 1930. Serial No. 37,414. Term of patent 8½ years.

To all whom it may concern:

Be it known that I, GEORGE SAKIER, a citizen of the United States, residing at New York, in the county of New York and State of New York, have invented a new, original, and ornamental Design for a Tumbler or Similar Article, of which the following is a specification, reference being had to the accompanying drawings, forming part thereof.

In the drawings:

Fig. 1 is a side elevational view of a tumbler or similar article, showing my new design; and

Fig. 2 is a sectional view thereof, taken on the line II—II of Fig. 1, looking in the direction of the arrows.

I claim:

The ornamental design for a tumbler or similar article, as shown.

GEORGE SAKIER.
